UNITED STATES PATENT OFFICE

HARRISON R. WILLIAMS, OF NEW YORK, N. Y.

PACKING

Application filed March 9, 1927. Serial No. 173,909.

- This invention relates to improvements in packing intended for use as a protecting padding or lining for boxes or other containers intended to hold articles that are easily crushed or injured by jarring or scratching.
- 5 It is an object of the invention to provide a packing which is cheap to manufacture, which is extremely soft and therefore shock absorbing, and which is water repellent, for protecting the articles from damage by rough handling or by moisture. It is a further object to provide a packing, the outer surface of which is indented to give a novel construction having increased resiliency and strength.
- 10 Other objects and advantages will herein-after appear.
- Figure 1 of the drawings is a fragmentary perspective view of a preferred illustrative embodiment of the invention;
- 15 Figure 2 is a view in section taken along line 2—2 of Figure 1, and
- Figure 3 is a perspective view of a modification.
- 20 The packing comprises a body portion 1 of loosely felted wood fibers which are adhesively connected to a water repellent backing 3 of glazed paper desirably of the type of paper commercially known as "glassine". However, if desired, wax paper, or a low grade of wrapping paper or other material may be used as a backing. The body portion 1 consists of a single, thick padding layer of wood fibers which are chemically treated
- 25 to make them soft and cottony the material being, for example, like that described as the primary product in my pending application, Serial No. 111,390, filed May 24, 1926, for wood-pulp products and the like. These
- 30 form a packing felt which is resilient and very soft and therefore affords substantial protection to soft articles or easily breakable articles such as candy, eggs, etc.
- The making of the padding body of felted
- 35 wood fibers results in the production of a packing which is less expensive, and more effective than packings heretofore used for like purposes.
- In the manufacture of my improved pack-
- 40 ing, the outer surface of the wood-fiber is preferably though not necessarily covered with a suitable skin, 2. This skin may consist of either a sheet of thin paper, or it may be formed of the fibers themselves, by incorporating the outer layer with a thickening material which in some cases may resemble a glaze. The coating of whatever type used having been applied, the outer surface is indented by suitable means, so as to give the appearance of Figure 2, producing
- 45 lines of indentation *a*, along which the outer coating is brought substantially into contact with the glassine under layer 3. In the usual case the outer layer or skin 2 will not quite meet the backing but will include a rather thin layer of fibers as shown in Figure 2. Such layer, however, does not prevent the outer skin 2 from adhering along the lines of indentation and furthermore gives added
- 50 strength to the fabric. Previously the layer of material 7 has been fed out upon the glassine or other layer 3 and caused to adhere thereto by means of a layer of adhesive 4. In this way a packing is produced which in a borrowed sense is tufted and which has increased resiliency by virtue of such construction. This is important when the packing is used for candy wadding as it enables the wadding to adjust itself between the top of the box and the candy, while preserving the
- 55 necessary resiliency. Moreover, the produced fabric is conveniently parted along such lines of indentation.
- If desired, the indenting of the surface of the packing instead of extending substantially all the way to the bottom layer or covering may be merely embossed whereby the indentation extends only a slight distance interiorly of the packing. This construction is shown in Figure 3 and achieves the result of causing the digested wood-fibre or other material better to adhere to the glassine or other backing. While this form preserves certain features of the invention and
- 60 is satisfactory for many purposes, I do not prefer it to the tufted type described.
- An example of a suitable thickening agent to be employed is a mixture in water of starch, gum arabic and a small quantity of

glue, cooked with steam with tallow and a small amount of glycerine.

Such packings of the prior art ordinarily consist of a multiplicity of plies of tissue paper. The manufacture of these laminated tissue paper packings necessitates the use of expensive paper manufacturing machinery, and this machinery must be used for manufacturing each individual paper ply separately. The numerous separately manufactured plies must then be assembled, and this assembly is necessarily complicated by the fact that a large number of plies go into the manufacture of each packing.

15 The present packing in either of the forms shown is softer and more shock absorbing than tissue paper packing and therefore affords a greater measure of protection to the articles in the container than previous packings of like thickness. It may, moreover, be constructed of any thickness desired without increasing the number of manufacturing steps and without complicating the assembly.

20 Variations may be resorted to within the scope of the invention and parts of the improvements may be used without others.

25 What I claim is:

30 1. A packing sheet for fragile articles consisting of soft, unlaminated, loosely felted fibers and a backing of thin, relatively strong fabric, said soft material having an outer skin and having spaced, intersecting lines of indentation in the soft material such that said outer coating is substantially united to the backing along such lines of indentation, thereby forming a tufted construction.

35 2. A packing sheet for fragile articles consisting of a backing of thin relatively strong fabric and a relatively thick unitary, substantially homogeneous, padding of soft, loosely felted unlaminated wood fiber and containing an outer skin on the outer surface thereof formed of the padding material, said padding layer having indentations in its surface so as to cause the skin to substantially extend to said backing along the lines of the indentation, such indentations being arranged so as to give the sheeting a tufted construction.

40 3. A packing sheet for fragile articles consisting of a backing of thin, relatively strong fabric, and a relatively thick, uniform and substantially homogeneous unlaminated padding of soft, loosely felted wood fibre, and 45 having an outer skin formed of the fibres themselves impregnated by a suitable thickening agent.

45 In testimony whereof I have affixed my signature to this specification.

50 HARRISON R. WILLIAMS.
